UNITED STATES PATENT OFFICE.

JESSE FAIRFIELD CARPENTER, OF WASHINGTON, DISTRICT OF COLUMBIA.

VALVE FOR AIR-BRAKES.

SPECIFICATION forming part of Letters Patent No. 606,513, dated June 28, 1898.

Application filed March 18, 1892. Serial No. 425,411. (No model.)

To all whom it may concern:

Be it known that I, JESSE FAIRFIELD CARPENTER, a citizen of the United States, residing at Washington, in the District of Columbia, have invented a certain new and useful Improvement in Valves for Air-Brakes, of which the following is a full, clear, and exact description.

The main object of this invention is to provide a quick-acting valve for air-brakes for railway-trains.

The invention consists in combining with an ordinary automatic triple valve another valve mechanism which is responsive to the pressures in the train-pipe and in the reservoir under certain conditions and is at all times independent of any movement of the triple valve proper, all as I will proceed now more particularly to set forth and finally claim.

In the accompanying drawings, illustrating my invention, in the two figures of which like parts are similarly designated, Figure 1 is a longitudinal section; and Fig. 2 is a cross-sectional elevation taken substantially in the plane of line $x-x$, Fig. 1.

The triple valve may be of the ordinary automatic type, consisting of the casing a , piston b in chamber c , piston-rod d , having the collars d' d'' to work the slide-valve e , which controls the cylinder-port f and exhaust-port g , the valve-spring e' , the reservoir connection h , and train-pipe connection i . The train-pipe pressure passes through the channel i into the cylinder c and moves the piston to the position shown in Fig. 1, thereby letting air into the auxiliary reservoir through channel j and exhausting the brake-cylinder. Upon reduction of the train-pipe pressure the reservoir-pressure forces the piston in the opposite direction, closes the exhaust, and opens communication between the auxiliary reservoir and brake-cylinder, all as usual.

I prefer to fix to the triple-valve casing the casing k of my independent quick-acting-valve mechanism and to provide therein the chamber l and nipple m for connection with the train-pipe, and this chamber l opens into the channel i . The chamber l is divided by a flexible diaphragm n , having affixed a saddle or yoke o , in which is arranged a valve p , controlling a duct q , which communicates

directly or else indirectly through check-valve r with the brake-cylinder. This duct projects as a nose into the pressure-chamber l . The valve p is normally seated by spring s , and suitable guides, substantially as shown at t and u , may be employed for the diaphragm and valve p , respectively. The check-valve r may be provided also with the seating-spring v , arranged around a lug v' of the screw-cap v^2 .

The chamber above the diaphragm n is in the triple-valve casing and is in communication with the auxiliary reservoir by an independent duct or pipe n' , or it may be supplied otherwise with pressure to cause it to be responsive to the pressure below it.

The operation of my quick-acting valve is as follows: The diaphragm is suspended in equilibrium. Any slight reduction of pressure in the train-pipe to apply the brake will be balanced by the spring s , and the valve p will remain closed; but a further or considerable reduction of pressure in the train-pipe will result in the auxiliary-reservoir pressure predominating, and hence acting upon the upper face of the diaphragm and causing it to descend and open the valve p , which will let in the train-pipe pressure through the duct q . This pressure will open the valve r if it be employed, and the air will pass from the duct q directly to the brake-cylinder. Upon restoration of pressure in the train-pipe the valve p will seat and close the duct, and the check-valve r will seat also. By this arrangement pressure from the train-pipe or main reservoir may be used in addition to pressure from the auxiliary reservoir for setting the brakes.

I avoid the use of stuffing-boxes, double-seated valves, and other complications for controlling the through-passage from the train-pipe to the brake-cylinder by means of the projection of the duct q into the chamber l , and holding its valve seated by a yoke or saddle which straddles such duct, and itself is suspended from the diaphragm, and these peculiar features of construction I deem a new and valuable portion of my invention.

It will be observed that this quick-acting valve is wholly independent of any movement of the triple valve, and this also is original with me in this form.

The casings a and k , when united substan-

tially as shown in the drawings, constitute practically a single body or shell in which both the triple valve and the quick-acting valve are located and are readily accessible.

5. What I claim is—

1. In a fluid-pressure brake, the combination with a triple-valve mechanism, of a quick-acting-valve mechanism consisting of a piston or diaphragm exposed on one side to auxiliary-reservoir pressure and on the other to train-pipe pressure, a valve operated by said piston or diaphragm, and a passage from the train-pipe to the brake-cylinder controlled by the said valve, the two valve mechanisms being located in a casing common to both, substantially as described.
2. In a fluid-pressure brake, the combination with a triple-valve mechanism, of a quick-acting-valve mechanism consisting of a piston or diaphragm exposed on one side to auxiliary-reservoir pressure and on the other to train-pipe pressure, a valve operated by said piston or diaphragm, a passage from the train-pipe to the brake-cylinder controlled by said valve, and a check-valve in said passage, the two valve mechanisms being located in a casing common to both, substantially as described.
3. A quick-acting-valve mechanism for air-brakes, comprising a diaphragm suspended in a chamber open on one side of such diaphragm to the train-pipe pressure, and on the other to the auxiliary-reservoir pressure, and movable only under an abnormal reduction of pressure in the train-pipe, a duct leading from the train-pipe side of the diaphragm to the brake-cylinder, and a valve operated by the diaphragm for controlling the said duct, in combination with a triple valve and independent of any movement thereof, and a body or shell common to the two valves, substantially as described.
4. A quick-acting-valve mechanism for air-brakes, comprising a diaphragm suspended in a chamber open on one side of such diaphragm to the train-pipe pressure, and on the other to the auxiliary-reservoir pressure, and movable only under an abnormal reduction of pressure in the train-pipe, a duct projecting into the chamber and leading from the train-pipe side of the diaphragm to the brake-cylinder, a valve suspended from the diaphragm and operated by the diaphragm for controlling the said duct, and a check-valve in said duct seating with the exhaust from the brake-cylinder, combined with the triple

valve, and a body or shell common to and enclosing the triple valve and the quick-acting valve, substantially as described.

5. The combination with an ordinary automatic triple valve, of a quick-acting-valve mechanism, and a body or shell common to both, said quick-acting valve comprising a diaphragm suspended in a chamber which is made in said body or shell and open on one side of such diaphragm to the train-pipe pressure, and on the other to the auxiliary-reservoir pressure, the diaphragm being movable only under an abnormal reduction of pressure in the train-pipe, a duct leading from the train-pipe side of the diaphragm to the brake-cylinder, and a valve operated by the diaphragm for controlling the said duct, substantially as described.

6. In a quick-acting-valve mechanism for air-brakes the combination of the chamber into which the train-pipe enters, a duct projecting into such chamber, a valve seating in the mouth of such duct, and a diaphragm always open to auxiliary-reservoir pressure and from which diaphragm said valve is suspended, substantially as described.

7. In a quick-acting-valve mechanism for air-brakes the combination with an ordinary triple valve, of the chamber into which the train-pipe enters, a duct projecting into such chamber, a valve seating in the mouth of such duct, a saddle or yoke in which such valve is arranged, and a diaphragm always open to auxiliary-reservoir pressure and from which diaphragm such valve is suspended, the said valve and diaphragm operating independently of any movement of the ordinary triple valve, substantially as described.

8. In a quick-acting-valve mechanism for air-brakes the combination of the chamber into which the train-pipe enters, a duct projecting into such chamber, a valve seating in the mouth of such duct, a saddle or yoke in which such valve is arranged, and a diaphragm always open to auxiliary-reservoir pressure from which diaphragm said saddle or yoke is suspended, substantially as described.

In testimony whereof I have hereunto set my hand this 17th day of March, A. D. 1892.

J. FAIRFIELD CARPENTER.
